US0D1056440S

(12) United States Design Patent (10) Patent No.: US D1,056,440 S
(45) Date of Patent: * Jan. 7, 2025

(54) SHOE

(71) Applicant: NIKE, Inc., Beaverton, OR (US)

(72) Inventor: Benjamin Nethongkome, Beaverton, OR (US)

(73) Assignee: NIKE, Inc., Beaverton, OR (US)

() Term: 15 Years

(21) Appl. No.: 29/895,655

(22) Filed: Jun. 23, 2023

(51) LOC (15) Cl. 02-04

(52) U.S. Cl.

USPC D2/972; D2/977

(58) Field of Classification Search

USPC D2/902-912, 947, 969-978, 946

(57) CLAIM

The ornamental design for a shoe as shown and described.

DESCRIPTION

FIG. 1 is a rear perspective view of a shoe showing my new design;

FIG. 2 is a rear view thereof;

FIG. 3 is an opposite side rear perspective view thereof;

FIG. 4 is a rear perspective view of an alternative embodiment of a shoe showing my new design;

FIG. 5 is a rear view thereof; and,

FIG. 6 is an opposite side rear perspective view thereof.

The broken lines immediately adjacent to the shaded area define the bounds of the claimed design and form no part thereof. In FIGS. 4-6, the broken lines depicting the inner pull loop form no part of the claimed design. The broken lines depicting the remainder of the shoe form no part of the claimed design.

1 Claim, 6 Drawing Sheets
